Primary Examiner — Elizabeth J Oswecki*(74) Attorney, Agent, or Firm* — Pollack, P.C.(57) **CLAIM**

The ornamental design for a perfume bottle, substantially as shown and described.

DESCRIPTION

FIG. 1 is a perspective view of a perfume bottle showing my new design;

FIG. 2 is a front view of the perfume bottle shown in FIG. 1, the rear view being a mirror image thereof;

FIG. 3 is a side view of the perfume bottle shown in FIG. 1, the opposite side view being a mirror image thereof;

FIG. 4 is a bottom view of the perfume bottle set forth in FIG. 1; and,

FIG. 5 is a top view of the perfume bottle shown in FIG. 1. The cap-engagement area shown with a shadow line in broken lines is for environmental purposes, and forms no part of the claimed design.
